DESIGN FOR A TOM-TOM OR SIMILAR ARTICLE

Antero V. Rivero, Miami, Fla.

Application October 10, 1944, Serial No. 115,698

Term of patent 14 years

(Cl. D34—15)

To all whom it may concern:

Be it known that I, Antero V. Rivero, a citizen of the United States residing at Miami, in the county of Dade and State of Florida, have invented a new, original, and ornamental Design for a Tom-Tom or Similar Article, of which the following is a specification, reference being had to the accompanying drawing, forming part thereof.

Figure 1 is a front elevational view of a tom-tom or similar article, showing my new design, and

Figure 2 is an edge elevational view thereof.

The back of the tom-tom is substantially plain.

I claim:

The ornamental design for a tom-tom or similar article, as shown and described.

ANTERO V. RIVERO.
